MEANS FOR STRIPPING CARDING APPARATUS

William H. Goldsmith, Jr., Brookline, Mass., assignor to Abington Textile Machinery Works, Boston, Mass., a trust of Massachusetts

Application August 19, 1943, Serial No. 499,268

14 Claims. (Cl. 19—109)

1

The present invention relates to card stripping apparatus for stripping card clothed cylinders. More particularly, the invention is concerned with apparatus by which the stripping may be carried out automatically without stopping the machine or otherwise interfering with continuous production of the lap. Certain aspects of the invention are directed to improvements in the stripping apparatus comprising the subject matter of my prior Patent No. 2,327,349, issued August 24, 1943.

That application discloses a method and apparatus for pneumatic stripping wherein suction is applied to relatively narrow strips of the carding cylinder according to a predetermined pattern or sequence, the suction being applied briefly to one strip after another in succession so as to effect a substantially continuous stripping with but slight effect on the finished web. The card is thus enabled to operate continuously, instead of being forced to shut down for periodic over-all stripping as required by conventional practice.

In the machine of the prior application, the stripping apparatus is disposed, relative to the carding cylinder, beyond the point of delivery of the web to the doffer, so as to operate on the portion of the mat that remains on the cylinder. However, in vacuum stripping, it has been found that there is some tendency, especially at the commencement of each stripping, to loosen but to remove only partially the residue of fiber in the zone of stripping. That is, upon the application of suction at any given area, some time must elapse before it becomes effective to strip to the full depth of the wires, and in the meantime, the cylinder has advanced beyond the zone of effectiveness of the suction. With the stripping apparatus positioned as above described, it appears that these loosened but unremoved fibers or tailings, frequently containing foreign matter impacted therewith, are carried into the clean fibers thereafter received by the cylinder from the licker-in and are consequently incorporated in the web.

It has been found that this condition may be substantially improved if the stripping is carried out within the zone customarily occupied by the flats, preferably close to the licker-in, in the region where a clean flat first contacts the cylinder and the oncoming new cotton. In this location, such material as is not entirely removed during the initiation of operation of a suction nozzle is, if loosened at all, brought up to a point where the close-setting flat wires effectively remove the tailings. Furthermore, the operation of

2

the flats aids in eliminating any non-uniformity in the lap that may result from the localized stripping operations, with the result that the web supplied to the doffer is at all times uniform and uncontaminated, and may be produced without interruption for periodic overall stripping.

To apply suction selectively to small areas of the card cylinder, the machine of the prior application employs a nozzle member having a plurality of closely spaced suction passages directed towards the cylinder and arranged to cover the entire length of the cylinder. Communicating with these passages is a suction manifold, connected to a source of suction. Through the provision of control means intermediate the manifold and the passages, one after another of the passages is placed in communication with the suction manifold according to a predetermined sequence so that the entire width of the cylinder is treated during the course of a cycle of operation. The control means is in the form of an endless belt, provided with accurately located apertures which register with one or another of the suction passages to provide communication between the latter and the suction manifold, the belt being advanced in step by step fashion between the manifold and the adjacent ends of the suction passages. However, certain difficulties have been found with the operation of this apparatus due to clogging by fibers which are caught in transit by the belt as the latter moves to cut off a passage following the application of suction through that passage. Furthermore, it has been found desirable to provide greater flexibility of control of the suction periods than that afforded by varying the rate of belt advance alone.

It is therefore an object of the present invention to provide pneumatic stripping apparatus of improved construction and arrangement, so as to operate automatically and effectively and thereby make possible the uninterrupted production of a uniform and uncontaminated web with a minimum of waste.

More specifically, the invention has as an object the provision of pneumatic stripping apparatus operating automatically to strip successive narrow lateral strips from the mat in predetermined sequence, the apparatus being adapted to function effectively without clogging for long periods of time.

In accordance with these objects the invention contemplates, as a feature thereof, the provision of pneumatic card stripping apparatus adapted to strip narrow lateral strips of the card cylinder according to a predetermined sequence, the strip-

ping being carried out on that portion of the cylinder between the licker-in and the doffer, in the region of operation of the travelling flats.

Another feature of the invention relates to pneumatic stripping apparatus adapted to strip successive narrow lateral strips of the card cylinder according to a predetermined sequence, the suction being applied to the card cylinder through a plurality of suction nozzles from a suction manifold, said apparatus including means for terminating the suction period at each of the nozzles by opening the manifold to atmosphere, thereby clearing the passages of fibers in transit.

The invention further contemplates, as a feature, the provision of pneumatic stripping apparatus arranged to operate in the portion of the machine occupied by the travelling flats and adjacent the licker-in, the apparatus comprising suction nozzles carried by the flats and disposed in various positions laterally in successive flats according to a predetermined pattern, a suction manifold, and means dependent at least in part on the progression of the flats about the carding cylinder for establishing and terminating suction communication between the manifold and the suction nozzles to strip narrow lateral strips of the cylinder in predetermined sequence.

In the accompanying drawings, Fig. 1 illustrates a partially diagrammatic longitudinal section of a standard cotton card embodying stripping apparatus according to the preferred embodiment of the invention; Fig. 2 is a detail view, partly in section, of a portion of the stripping apparatus shown in Fig. 1; Fig. 3 is a fragmentary top plan view of certain of the parts shown in Fig. 2; Fig. 4 is a detail view of shut-off valve mechanism; Fig. 5 is a view in side elevation, partly broken away, of a modified form of stripping apparatus; Figs. 6 and 7 are detail views of the apparatus shown in Fig. 5, taken at different times in the operation of the apparatus; and Figs. 8 and 9 are detail sectional views of the edge portion of the suction control belt employed in the embodiment shown in Fig. 5.

The card illustrated in Fig. 1 is, except in respect to the stripping apparatus to be described, of conventional design, the principal elements being the licker-in 12, carding cylinder 14 and doffer 16. During the passage of the lap 18 from licker-in to doffer, the lap is engaged by a series of flats 20 which are moved slowly over the surface of the carding cylinder by means of driving chains 22 to which the flats are connected. Driving means for the flats are illustrated as comprising belt or chain drive 24 from the carding cylinder to a jack shaft 26 which in turn drives shaft 28 through double reduction worm gearing 30 and 32 to advance the flats a distance equal to the spacing between successive flats in approximately twenty-seven seconds. Other types of driving connections and different rates of flat advance may of course be provided as desired.

To perform, during continued operation of the machine, automatic vacuum stripping of the card cylinder in the region which has been found most favorable from the standpoint of continuous production of a uniform and uncontaminated lap from which a minimum of fiber has been removed by the stripping operation, the stripping apparatus of the invention is disposed in the flat area of the machine and operates in conjunction with the flats themselves. By stripping in this zone, rather than in that portion of the carding cylinder between the doffer and the licker-in, the fibers or tailings which are loos-

ened but not removed during the initial application of suction at each nozzle are not carried along into the new cotton received from the licker-in and so blanketed thereby that the flat wires

5 are relatively ineffective to remove these tailings. Instead, the stripping is carried out, as herein-after described, in that region of the cylinder within which the flats operate on the new cotton received by the carding cylinder from the licker-in, with the result that any tailings loosened or released during the initial application of suction at the beginning of a furrow are immediately engaged by the flat wires and picked up thereby. The dirty fibers are thus effectively eliminated 10 from the finished lap, permitting the manufacture of yarn of high quality with less combing, and in many cases without the necessity of any combing operation.

In accordance with the preferred arrangement 20 for carrying out the stripping operation in this region of the carding cylinder, the flats are provided with suction nozzles 40 which extend into close proximity to the tops of the card wires 42. These nozzles may be in the form of tubes of 25 square or rectangular cross-section and are conveniently mounted in the flats by passing the tubes through a suitable aperture provided in one of the webs 44 of the flat body, which is generally of inverted T-shaped section. At their 30 top or outer ends, the tubes are positioned by a strip 46 secured to and extending the full length of the central web 48 of each flat. The tops of the tubes are ground off flush with the top surface of the strips 46, while the mouths are 35 ground to lie in the same plane as the ends of the flat wires 50, this latter grinding operation preferably being carried out along with the grinding of the flat wires. In accordance with preferred practice, this plane is not exactly tangent to the periphery of the card wires at the flat, but is at a slight angle thereto, converging in the direction of rotation of the card cylinder.

To carry out the method of sequential stripping of narrow strips of the card cylinder according to a predetermined pattern, each flat is 45 preferably provided with a single suction nozzle, the nozzles in successive flats being positioned in the flats transversely thereof according to a pattern similar to that employed for the apertures 50 in the endless belt forming a part of the stripping apparatus disclosed in prior Patent No. 2,327,349, above referred to. According to this arrangement, illustrated in fragmentary fashion in Fig. 3, the nozzles in successive flats, typified by nozzles 52, 54, 56, are disposed alternately on either side of a center line (such center line being indicated at 58) and at progressively increasing distances from said line, so as to strip progressively from the center outwardly while alternating from one side to the other of the center line. The spacing between successive nozzles on each side of the center line is made somewhat greater than the nozzle width, this spacing continuing throughout one series of nozzles. In the succeeding series, the nozzles are arranged in the flats intermediate the positions of nozzles of the preceding series, to enable all portions of the card cylinder to receive stripping treatment.

Suction is supplied to each of said nozzles in 70 succession by means of a suction manifold 60 extending substantially the full length of the carding cylinder and preferably located in the region where the clean flats first engage the card cylinder, that is, near the licker-in. The manifold, which is connected in any suitable manner,

as by hose or flexible pipe (not shown) to a vacuum pump or other source of suction (likewise not shown), is formed with a long continuous slot 62 in one wall so as to permit communication, at one time or another, with the top opening of the suction nozzle of each flat as the latter moves into position of registration with the manifold. During registration, the slot is closed, except for communication with the nozzle, by the top plate 46 with which each flat is provided. The contacting face of the manifold is preferably provided with resilient sealing material 63 such as leather or rubber.

The flats, in their normal operation, progress slowly around the carding cylinder, and this movement serves to bring successive nozzles into position of registration with the slot in the manifold. To insure proper suction communication between manifold and nozzle at these times of registration, the manifold is mounted for bodily movement toward and from the flats in timed relation to the rate of flat advance. To this end, the manifold is carried on levers 64 arranged for rocking movement about shaft 66. The levers are given limited rocking movement by means of cam discs 68 which are engaged by followers 70 at the ends of levers 64.

A yielding connection affording two degrees of freedom is provided between the levers and the manifold. Guide studs 72 loosely received in the levers and carrying compression springs 74 enable the manifold yieldingly to be urged into engagement with the top plate of the flat when the cam is in a position where the follower 70 is at the low point 76. During such time as the manifold is in contact with the flat, the manifold may partake of limited translational movement along with the flat, this being permitted by tension springs 78 which, when the manifold is disengaged from the flat, draw the manifold back to a position determined by adjustable stop pins 80 preparatory to being lowered into engagement with the following flat to initiate suction communication with the nozzle thereof.

Driving connections for moving the nozzle into and out of engagement with successive flats are provided from the shaft 26 of the flat-driving mechanism. These connections involve a cam 82 on said shaft, a bell crank 84 provided with a cam follower, and a link 86 from the bell crank to an arm 88 mounted to rock about a center concentric with cam disc 68. Pawl and ratchet connections 90 and 92 translate rocking movement of the arm into slow rotation of the cam disc. The parts are preferably so proportioned relative to the driving connections for the flats as to provide relatively brief engagement between the manifold and each flat. For example, if the interval between the arrival of successive flats at registration with the manifold is of the order of twenty-seven seconds, the manifold may be maintained in engagement with the flat for perhaps two seconds.

The stripping is therefore not continuous in the sense that at all times some portion of the card cylinder is being subjected to stripping action. The stripping is, however, continuous insofar as the removal of material in a succession of increments makes possible the continuous production of a uniform and uncontaminated lap. The utilization of a relatively small fraction of the available time for stripping at each nozzle has proven entirely practical because of the effectiveness of stripping according to this technique of removing the material in a continuing suc-

sion of increments during normal operation of the machine. By reducing the stripping interval at each nozzle, the amount of material removed by the stripping may be limited only to that necessary for maintaining the cylinder in the condition for most effective carding.

While each suction period is effectively terminated by breaking suction communication between the manifold and the individual suction nozzles in the flat, this results in opening the full length of the slot to atmosphere, with consequent waste of energy due to the additional volume of air to be handled. A control valve is therefore provided in the line between manifold and source of suction, the valve being actuated in timed relation to the establishment and termination of suction communication between manifold and the suction nozzle in each flat.

Such a valve may be of any suitable construction and arrangement, that illustrated in Fig. 4 comprising a slide valve 100 provided with an aperture 102 and adapted to be reciprocated across opposing faces of the supply conduit 104 by a lever 106 rocked by a cam 108. This cam may conveniently be mounted on the same shaft with the cam disc by which the manifold is moved into and out of engagement with each flat.

The timing of the cam discs is so arranged that suction is supplied to the conduit substantially in synchronism with the establishment of communication between manifold and the suction nozzle of the flat. Suction is not cut off, however, until an appreciable time interval after communication between manifold and suction nozzle has been terminated by withdrawing the manifold from engagement with the flat. Upon separation of manifold and nozzle, stripping by that nozzle ceases and air rushes directly into the slot along the full length thereof. This inrushing air quickly cleans the passages of all loose fibers, carrying along past the cut-off valve toward the receiver any fibers that were in transit when suction ceased at the nozzle mouth. Thereafter, the valve is moved to closed position, without risk of clogging by reason of intercepted fibers, since only clean air, free of fibers, is then flowing through manifold and connecting pipes.

This sequence of operations is of important benefit since all parts, particularly those involving surfaces which must periodically engage in substantially air-tight contact to provide effective stripping and avoid wasteful leakage, are automatically cleared of loose fibers, and the possibility of clogging through interception of fibers in transit is eliminated. At the same time, suction requirements are kept low, so that a source of suction of relatively small volumetric capacity is sufficient to provide effective stripping during continuous operation of the machine.

The feature of the invention relating to termination of suction at the nozzles by opening the manifold to atmosphere and thereby by-passing the suction nozzle may be embodied to advantage in stripping apparatus of the type disclosed in my prior application, employing an endless belt having approximately disposed apertures to control the stripping sequence.

In this embodiment, illustrated in Figs. 5 to 7, the suction nozzles are arranged in closely spaced relation in a nozzle member 120 fixed in the machine frame to maintain the nozzle mouths close to the carding cylinder. This nozzle member, and other elements of the apparatus are, except as hereinafter specifically described, similar to those of the aforesaid application, to which reference

may be made for a complete disclosure. A manifold 122 communicating with a source of suction, not shown, is provided with a continuous slot 124 extending the length of the nozzle member.

The sequence of operation of the suction nozzles is controlled by an endless belt 126 having apertures arranged as in the prior application and driven by sprockets 128 engaging the reinforced margins of the belt. Such reinforcement may comprise perforated metal strips 130 secured at intervals by open rivets 132 (see Figs. 8 and 9). A shut-off valve, which may be similar to that illustrated in Fig. 4, is disposed in the conduit between manifold and suction supply.

The manifold is positioned beneath the nozzle member in guideways 136 which permit movement of the manifold toward and from the nozzles. The manifold is reciprocated in timed relation to belt advance by means of cams 138 secured to a shaft 140 journaled beneath the manifold and rotated by chain and sprocket connections 142, 144 from shaft 146 from which the step-wise drive for the endless belt is derived. The cams are engaged by cam followers 148 mounted on the manifold, tension springs 150 being employed to cause the manifold position to follow the cam track.

As in the embodiment of the prior application, the endless belt runs between the manifold and the nozzle member. In order that the belt may partake, at least in part, of the periodic movement toward and away from the nozzles, the belt is so placed as to be forced upwardly a slight amount by the top of the manifold. As a result, the belt tends to follow the manifold when the latter is moved away from the nozzle member. As the manifold approaches its lowermost position, however, the belt is intercepted by rods 152 extending across the machine on each side of the manifold. Upon further movement of the manifold away from the nozzle member, the belt remains supported by the rods, and clearance thus occurs between the belt and the manifold.

The sequence of operations of belt, manifold, and suction shut-off valve in initiating and terminating each suction period at the different nozzles is arranged not only to permit control of the duration of each stripping period, but also to insure that each suction passage is cleared of fibers and other foreign matter before the belt advances to bring a different aperture into registry. By so doing, the possibility is avoided of fibers in transit being interrupted by the belt and carried along so as to interfere with the proper operation of the belt.

This result is accomplished by causing the suction manifold and endless belt to move out of engagement with the nozzle member before each step-wise advance of the belt. This results in breaking suction communication with the particular nozzle passage then active, and thus terminating the stripping through that nozzle. Initially, due to the clearance between the belt and the suction nozzles resulting from the partial lowering of the manifold, air flow continues to take place through the belt aperture into the manifold and thence to the source of suction, so that any fibers which were just leaving the cylinder and in transit when the disengagement took place are carried through the belt aperture and into the manifold so as to clear the passage and adjacent belt aperture of loose fibers before the belt advances to cut off that particular passage. As the manifold reaches its fully lowered position, clearance develops between belt and mani-

fold, causing the opposing surfaces of these parts likewise to be cleaned of fibers. Thereafter, the shut-off valve is moved to closed position to avoid loss of suction head and waste of energy. Upon

5 step-wise belt advance to bring another aperture into registration with its appropriate suction nozzle, the manifold is raised to establish suction communication, and the shut-off valve opened to initiate a new suction period. The relative length 10 of each suction period may thus be accurately regulated to provide the desired amount of stripping at each nozzle. Accordingly, only so much material need be stripped as is necessary to provide proper cleaning of the wires, and consequently waste of material may be reduced to a 15 minimum.

While both embodiments of the invention herein described are highly effective in providing what may be termed continuous stripping by automatically removing small increments of the web in a more or less continuous succession without interrupting the production of the web, the construction illustrated by Figs. 1 to 4, wherein this method of stripping is carried out in the flat area, between the licker-in and the doffer, is 20 especially advantageous for high quality carding. Accordingly, it is to be understood that this embodiment is to be preferred, since it makes possible the manufacture of high quality yarn with little and in many cases with no combing.

30 Having described the invention in its preferred form and an alternative embodiment thereof, I claim:

1. Means for stripping carding apparatus of the type having a plurality of flats arranged 35 transversely of the card clothed cylinder for progressive movement around the periphery of said cylinder in the zone between licker-in and doffer, said means comprising suction passages disposed in said flats and extending into close proximity to the surface of the cylinder, a suction manifold, and means for periodically establishing suction communication between the manifold and the suction passages in the flats.

2. Card stripping apparatus comprising a plurality of members arranged transversely of and adapted to be advanced in continuous succession around at least a portion of the periphery of a card clothed cylinder in proximity to the surface thereof, said members having suction passages 50 therethrough extending into close proximity to the surface of the cylinder, the passages being disposed in the members at various positions transversely thereof according to a predetermined sequence, a suction manifold, and means 55 for periodically establishing and terminating suction communication between suction manifold and one after another of the suction passages in the members according to said predetermined sequence.

60 3. Means for stripping carding apparatus of the type having a plurality of flats arranged transversely of the card clothed cylinder for progressive movement around the periphery of said cylinder in the region between licker-in and doffer, said means comprising suction passages disposed in said flats and extending into close proximity to the surface of the cylinder, said 65 passages being disposed in successive flats at various positions transversely thereof according to a predetermined sequence, a suction manifold, a valve in control of the suction induced therein, means for periodically establishing and terminating suction communication between the manifold and the suction passages in successive flats, 70 and means for actuating the valve in timed relation 75 to a predeter-

tion to said periodic operation to open said valve upon the establishment of suction communication and to close said valve after suction communication is terminated.

4. Means for stripping carding apparatus of the type having a plurality of flats arranged transversely of the card clothed cylinder for progressive movement around the periphery of said cylinder in the region between licker-in and doffer, said means comprising suction passages disposed in said flats and extending into close proximity to the surface of the cylinder, said passages being disposed in successive flats at various positions transversely thereof according to a predetermined sequence, a suction manifold, and means operating periodically in timed relation to the progression of the flats for bodily moving the manifold into engagement with each flat in succession during the period of substantial registry of each flat with the manifold, thereby to establish suction communication between the manifold and the suction nozzle of each flat in succession.

5. Means for stripping carding apparatus of the type having a plurality of flats arranged transversely of the card clothed cylinder for progressive movement around the periphery of said cylinder in the region between licker-in and doffer, said means comprising suction passages disposed in said flats and extending into close proximity to the surface of the cylinder, said passages being disposed in successive flats at various positions transversely thereof according to a predetermined sequence, a suction manifold, supporting means therefor including devices actuated periodically in timed relation to the progression of the flats to move the manifold into engagement with each of the flats in succession during the period of substantial registration of each flat with the manifold, said supporting means including yielding connections permitting limited translational movement of the manifold whereby suction communication between manifold and the suction nozzle in each of the flats may be maintained at least briefly as the flat progresses.

6. Card stripping apparatus comprising a member provided with a plurality of closely spaced suction passages extending into close proximity to the card cylinder and disposed in said member along the length of said cylinder, a suction manifold for supplying suction to said passages, said manifold being mounted for bodily movement toward and away from the member, selector means disposed intermediate the manifold and the suction passages for opening one after another of the passages to the suction manifold according to a predetermined sequence, and means operative in timed relation to the operation of the selector means to withdraw the manifold from the member to terminate the stripping and clear the selector means.

7. Card stripping apparatus comprising a nozzle member provided with a plurality of closely spaced suction passages extending into close proximity to the card cylinder and disposed in said member along the length of said cylinder, a suction manifold for supplying suction to said passages, selector means disposed intermediate the manifold and the suction passages for opening one after another of the passages to the suction manifold according to a predetermined sequence, and means for bodily moving the selector means and suction manifold out of engagement with the nozzle member prior to each oper-

ation of the selector means to terminate each suction period.

8. Card stripping apparatus comprising a nozzle member provided with a plurality of closely spaced suction passages extending into close proximity to the card cylinder and disposed in said member along the length of said cylinder, a suction manifold for supplying suction to said passages, said manifold being mounted for bodily movement toward and away from the nozzle member, selector means disposed intermediate the manifold and the suction passages for opening one after another of the passages to the suction manifold according to a predetermined sequence, means for periodically actuating the selector means to terminate the operation of one nozzle passage and initiate operation of a different passage, and means for bodily moving the suction manifold away from the nozzle member to separate the nozzle member, selector means, and suction manifold during each actuation of the selector means.

9. Card stripping apparatus comprising a nozzle member located adjacent the surface of a card clothed cylinder and extending lengthwise thereof, the member having a plurality of fixed, closely spaced suction passages therethrough, a suction manifold disposed in parallel relation to the member and movable toward and from the same, a surface having openings therein according to a predetermined pattern, said surface being disposed between the nozzle member and the suction manifold, means for periodically advancing said surface to cause one or another of the openings in the surface to register with a passage in the member and thereby provide communication with the suction manifold, and means for periodically moving the surface and suction manifold bodily away from the nozzle member and for thereafter moving the manifold away from the surface prior to each periodic advance of said surface.

10. Card stripping apparatus comprising a nozzle member provided with a plurality of closely spaced suction passages extending into close proximity to the card cylinder and disposed in said member along the length of said cylinder, a suction manifold for supplying suction to said passages, selector means comprising an endless belt disposed between the manifold and the nozzle member and provided with a series of apertures therein, means for advancing the belt periodically to open one after another of the suction passages to the manifold according to a predetermined sequence, means for periodically withdrawing the manifold from the nozzle member in timed relation to belt advance to terminate suction communication with the nozzle member prior to each advance of the belt, and means adapted to intercept the belt after limited withdrawing movement of the manifold to enable the manifold thereafter to withdraw from the belt.

11. Card stripping apparatus comprising a nozzle member provided with a plurality of closely spaced suction passages extending into close proximity to the card cylinder and disposed in said member along the length of said cylinder, a suction manifold for supplying suction to said passages, a valve in control of suction in said manifold, selector means disposed intermediate the manifold and the suction passages for opening one after another of the passages to the suction manifold according to a predetermined sequence, said manifold and selector means being mounted

for movement toward and from the nozzle member, and means for advancing and withdrawing the manifold and selector means and for actuating the selector means and the valve in timed relation to cause the manifold and selector means to be moved away from the nozzle member prior to closing of the control valve and change of opening by the selector means.

12. Card stripping apparatus comprising nozzle means having suction passages adapted to extend into close proximity to the surface of a card clothed cylinder, a suction manifold having a suction passage for applying suction to the nozzle passages, means for causing suction to be applied to the individual nozzle passages according to a predetermined sequence to cause successive strips of the cylinder to be stripped, and means for periodically separating spatially the manifold and the nozzle means to open the manifold to atmosphere intermediate the nozzle means and the manifold and thereby terminate the application of suction to said nozzle means.

13. Card stripping apparatus comprising nozzle means having suction passages adapted to extend into close proximity to the surface of a card clothed cylinder, suction means including a suction manifold having a suction passage for applying suction to individual suction passages in the nozzle means according to a predetermined sequence to strip successive strips from the cylinder, said nozzle and suction means being relatively shiftable to effect successive selection of individual suction passages according to said sequence and bodily separable to interrupt suction communication with the said suction passages by opening the suction passage in the manifold directly to atmosphere intermediate the nozzle means and the manifold, and mechanism for periodically effecting independent shifting and separating movements of the nozzle and

suction means in timed relation wherein said means are bodily separated to interrupt suction communication therebetween prior to relative shift thereof.

- 5 14. Card stripping apparatus comprising nozzle means having suction passages adapted to extend into close proximity to the surface of a card clothed cylinder, suction means including a suction manifold having a suction passage for applying suction to the nozzle passages, a valve in control of suction induced in the manifold, the nozzle and suction means being relatively shiftable to effect selection of individual suction passages in the nozzle means according to a predetermined sequence and bodily separable to interrupt suction communication with the said suction passage in the manifold directly to atmosphere intermediate the nozzle means and the manifold, and mechanism for effecting independent shifting and separating movements of the nozzle and suction means and for controlling the valve in timed relation thereto to cause separation of the nozzle and suction means prior to closing of the valve and relative shifting movement of said nozzle and suction means.
- 10 15. Card stripping apparatus comprising nozzle means having suction passages adapted to extend into close proximity to the surface of a card clothed cylinder, suction means including a suction manifold having a suction passage for applying suction to the nozzle passages, a valve in control of suction induced in the manifold, the nozzle and suction means being relatively shiftable to effect selection of individual suction passages in the nozzle means according to a predetermined sequence and bodily separable to interrupt suction communication with the said suction passage in the manifold directly to atmosphere intermediate the nozzle means and the manifold, and mechanism for effecting independent shifting and separating movements of the nozzle and suction means and for controlling the valve in timed relation thereto to cause separation of the nozzle and suction means prior to closing of the valve and relative shifting movement of said nozzle and suction means.
